His Attorney.

UNITED STATES PATENT OFFICE

ALAN S. FITZ GERALD, OF SCHENECTADY, NEW YORK, ASSIGNOR TO GENERAL ELECTRIC COMPANY, A CORPORATION OF NEW YORK

CASING

Application filed September 14, 1928. Serial No. 306,062.

My invention relates to improvements in casings for electroresponsive devices such as relays, meters and the like and more particularly to casings having the lead-in terminals 5 mounted in the base thereof, and has for its principal object the provision of an improved base in which the terminals may be arranged to adapt the casing for universal use. Another object of my invention is to provide an 10 improved casing of a form which permits the grouping of the devices on a switchboard in the minimum amount of surface.

In the construction of casings for electroresponsive devices, it has hitherto been difficult to provide for extra terminals or a rearrangement of the terminals already provided. This is objectionable since it is often desirable to use one type of casing for several different devices requiring different numbers of terminals 15 and various arrangements thereof. In accordance with my invention, this objection is overcome by an improved construction of the base for such casings whereby a number of terminal openings are provided to give the necessary scope for arranging the terminals 20 to meet the requirements of several different types of devices.

My invention will be better understood from the following description when considered in connection with the accompanying drawing and its scope will be pointed out in the appended claims.

Referring to the drawing, Fig. 1 is a perspective view, partly in section, of a casing embodying my invention and Fig. 2 is an exploded view of a part of the base of the casing shown in Fig. 1.

In Fig. 1 a casing 1 is shown mounted on a switchboard panel 2. The casing 1 includes a base 3, comprising telescoping members 4 and 5, and a cover 6. The supporting members 7 and 8 are attached to the member 5 and serve to support a relay or other device and to hold the cover 6 to the base 3 by means of a 45 fastening device 9.

Fig. 2 is a sectional view of the base 3 illustrating a portion of the telescoping members 4 and 5 and one of the terminals 10. The member 4 is attached to the board 2 by means 50 of bolts 11 and the member 5 is attached to

its cooperating member 4 by suitable means such as bolts 12. Washers 26 may be used between members 4 and 5 under the heads of bolts 12 in order to prevent the distortion of either or both members 4 and 5. These 55 washers may be used under each of the bolts 12 but it is preferable to use them only with the four corner bolts nearest the brackets 8. The terminal 10 is provided with a flanged insulating collar 13, which fits into registering holes 14 and 15 provided in the members 4 and 5 respectively. The flange 16 on the collar 13 projects beyond the periphery of collar 13 and is rigidly supported between the members 4 and 5. In the illustrated embodiment of my invention the members 4 and 5 are provided with sixteen pairs of registering holes 14 and 15 to accommodate terminals. Since that many terminals are seldom 60 needed by any one device, filler pieces 17 having the same outward shape as insulating collars 13 may be used to fill the remaining holes and the terminals may be arranged in any manner desired. It may also be desirable in some cases partially to punch out the 65 holes 14 and 15 during manufacture, leaving the material therein to be easily removed when the holes are needed. Packing washers 18 and 19 of yielding material such as cork may be used to prevent cracking the 70 insulating flange 16 when the bolts 12 are tightened.

The edges of members 4 and 5 which are preferably made of sheet metal, are turned up at substantially right angles to the body 75 of the members and are telescoped. The dimensions of the members 4 and 5 are such that sufficient space is provided between the upturned edges, or flanges, that the edge of the cover may be inserted. In this manner 80 the member 5 is allowed to project above the edge of the flange on member 4 so as to act as a guide for the cover 6. The bottom of the slot, formed by the flanges on members 4 and 5 provides a seat for the cover 6. This slot 85 is preferably relatively deep and a gasket 20 of suitable material such as felt is secured to the bottom of it, whereby a dust tight casing is insured. The member 4 may be upset 90 or dished, as indicated at 21, so that it may 95 100

set flush with the board 2 and still provide space for the nuts on bolts 12 and the ends of collars 13.

The cover 6 may be provided with a transparent face 22, such as glass through which the enclosed device may be seen. This face 22 is mounted in the cover by providing flanges 23 upon which the glass 22 rests, and a rim 24 which fits over the edge of the cover and is flanged to hold the face 22 against the flanges 23. The rim 24 is fastened to the cover 6 by bolts 25.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States, is:

- 20 1. The casing for electrical devices including a base and cover, said base including two telescoping members provided with registering openings, terminals provided with insulating collars and arranged to project through said openings and means for securing said members together whereby rigidly to support said terminals within said openings.
- 30 2. A casing for electrical devices including a base and cover, said base including two telescoping members provided with registering openings, terminals provided with insulating collars and arranged to project through said openings, and a flange on said collar arranged to be clamped between said telescoping members.
- 35 3. In a casing for electrical devices, a plurality of terminals, a base including two spaced members, a cover, means for insulating and supporting said terminals within said base arranged to be supported between said members, and means within said base for allowing different arrangements in the location of said terminals.
- 45 4. A casing comprising a cover and two flanged telescoping base members shaped to guide said cover between the flanges of said members and to form a seat for said cover.
- 50 5. A casing including a cover and two flanged telescoping base members shaped to provide a seat for said cover, one of said members projecting above the other to provide a guide for said cover whereby readily to seat the cover.

In witness whereof, I have hereunto set my hand this 13th day of September 1928.

ALAN S. FITZ GERALD.
